Primary Examiner — Kevin K Rudzinski*74) Attorney, Agent, or Firm* — HEA Law PLLC; Darrin A. Auito(57) **CLAIM**

The ornamental design for a nozzle, as shown and described.

DESCRIPTION

FIG. 1 is a front perspective view of a nozzle, showing our new design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken line showing of portions of the nozzle is for the purpose of illustrating environmental structure and forms no part of the claimed design. The dot-dash broken lines are boundary lines and form no part of the claimed design.
